UNITED STATES PATENT OFFICE.

MAX ISENSTEIN, OF NEW YORK, N. Y., ASSIGNOR TO HIMSELF AND LOUIS M. ROSENBERG, OF SAME PLACE.

DESIGN FOR A BELT.

SPECIFICATION forming part of Design No. 34,422, dated April 23, 1901.

Application filed March 22, 1901. Serial No. 52,448. Term of patent 3½ years.

To all whom it may concern:

Be it known that I, MAX ISENSTEIN, a citizen of the United States, residing in the city, county, and State of New York, have invented and produced a new and original Design for Belts, of which the following is a specification, reference being had to the accompanying drawings, forming part thereof.

Figure 1 is a plan view of the belt-body extended out, and Fig. 2 is a front perspective view showing substantially its appearance when buckled together as in use.

As shown in the drawings, the belt comprises two parts A and B. The part A is the larger of the two, being adapted to extend around the back and well over the hips of the wearer. Its middle portion is somewhat wider than the ends, and both the upper and lower edges are curved downwardly, forming an inverted flattened yoke. To the ends of A are secured buckles *a a* and retaining-straps *b b*. The part B consists of an inverted flattened

yoke, the lower edge of which, however, is pointed at the center and is substantially diamond-shaped. The ends of part B are 25 pointed and provided with perforations which engage the buckles *a a* on the part A.

When the belt is assembled and adjusted upon the wearer, the buckles are well forward to the front and because of the peculiar 30 shape already described have a slight downward tendency.

Having described my invention, what I claim as new, and desire to secure by Letters Patent, is—

The design for a belt or similar article substantially as herein shown and described.

Signed at the city, county, and State of New York this 8th day of March, 1901.

MAX ISENSTEIN.
